SHOE MACHINE AND METHOD

Karl Engel, Swampscott, Mass., assignor to United Shoe Machinery Corporation, Borough of Flemington, N. J., a corporation of New Jersey

Application June 8, 1939, Serial No. 278,117

27 Claims.

(Cl. 12—52)

The present invention relates to machines and methods for use in the manufacture of shoes having moccasin toe pieces, and is herein illustrated as embodied in a machine for assembling the toe piece with another shoe part, for example, a vamp member, and as practiced in a method of assembling moccasin toe pieces with the foreparts of shoes.

The term "shoe" is to be construed to include any and all types of footwear having moccasin toe pieces.

It is an object of the present invention to facilitate the assembling of a moccasin toe piece with the shoe part to which it is to be united and to eliminate much of the hand labor heretofore involved in the assembling operation.

With the above object in view, a feature of the invention consists in the provision, in a machine for use in the manufacture of shoes having moccasin toe pieces, of a toe piece engaging means herein illustrated as a fixed die having means projecting from its work engaging face for engaging the margin of a toe piece supported thereon, and means, herein illustrated as a movable die, constructed and arranged to coact with said fixed die to form a marginal flange in the toe piece, said dies being so constructed that the margin of a toe piece held between them is exposed for attachment to another shoe part. The illustrated movable die has the general outline of the toe piece on a smaller scale and its edge face affords an abutment against which the marginal flange formed in the toe piece is positioned in the course of the flange forming operation. In accordance with a further feature of the invention, the illustrated machine is provided with means, herein illustrated as a presser member, for pressing the top margin of a shoe part, for example a vamp member, against the marginal flange formed in the toe piece. When the machine is at rest, the presser member is located in a position remote from the fixed die in order to facilitate the positioning of the vamp member relatively to a toe piece held between the dies. In the operation of the machine, the presser member is first transferred from its remote position into longitudinal alinement with the supported toe piece and then advanced longitudinally of the toe piece to press the top margin of the vamp member against the margin of the piece.

It is a further object of the invention to improve the manufacture of shoes having moccasin toe pieces by providing for the formation in the toe piece of a convexity which will conform the

toe piece generally to the shape of the top of the forepart of the last on which the shoe is to be formed.

With the above object in view, the illustrated machine is provided with a pair of dies having the general shape of a moccasin toe piece and provided respectively with convex and concave surfaces constructed and arranged to co-act on a toe piece positioned between them to form a convexity therein and one of the dies is provided with a member for acting in the formation of a marginal flange in the toe piece. As herein illustrated, the toe piece is supported between a fixed die provided with a convex surface which acts against the central portion of the toe end of the toe piece and a movable die which, as herein illustrated, also functions as a flange forming member and is provided with a concave surface which coacts with the convex surface of the fixed member.

In one aspect thereof the present invention resides in a method of making shoes having moccasin toe pieces which comprises forming a marginal flange in a moccasin toe piece between dies, and while the toe piece is held between the dies securing the top margin of a shoe part, for example a vamp member, to the marginal flange of the toe piece.

In a further aspect thereof the present invention resides in a method of making shoes having moccasin toe pieces which comprises forming a convexity in the interior of a loose toe piece and thereafter attaching another shoe part to the margin of the toe piece. In forming a convexity in the toe piece, the forward margin of the toe piece is contracted and the contracted condition is maintained by securing a shoe part, for example, a vamp member, to the toe piece, edge to edge.

In another aspect, the invention comprises a method of making shoes having moccasin toe pieces characterized by the formation of a bulge in the toe end of the peripheral part of the shoe. As herein illustrated, the bulge is formed in the toe end of a vamp member pre-attached to a sole, in conjunction with the assembling of the vamp member to the margin of a toe piece. In the formation of the bulge in the vamp member the top margin at the toe end of the vamp member is bent inwardly over a form, and the bulged condition is secured and maintained by attaching the vamp member to the toe piece. In working the margin at the toe end of the vamp inwardly to form the bulge, the top margin at the sides of the vamp is contracted somewhat

while the margin at the toe end of the vamp remains substantially non-contracted. After the toe piece and the vamp member have been shaped, they are secured together by cement edge to edge and the contracted condition of the sides of the vamp is maintained by their attachment to non-contracted portions of the margin of the toe piece.

These and other aspects and features of the invention will now be described with reference to the accompanying drawings and pointed out in the appended claims.

In the drawings,

Fig. 1 is a side elevation of a machine embodying the present invention;

Fig. 2 is an enlarged view in side elevation illustrating certain operating parts of the machine with the work positioned between them;

Fig. 3 is an enlarged view in side elevation illustrating the machine in operation on a shoe, both the upper and lower portions of the machine being broken away and certain operating parts shown in section;

Fig. 4 is a section on the line IV—IV of Fig. 3;

Fig. 5 is a section through the center of the fixed die and a toe piece mounted thereon;

Fig. 6 is a section similar to Fig. 5 showing the toe piece molded between the dies;

Fig. 7 is a section similar to Fig. 6 showing the upstanding margin at the toe end of a vamp in position to be attached to the toe piece;

Fig. 8 is a section similar to Fig. 7 showing the margin of the vamp after attachment to the toe piece;

Fig. 9 is a section on the line IX—IX of Fig. 7;

Fig. 10 is a section on the line X—X of Fig. 8; and

Fig. 11 is a longitudinal section through the center of the forepart of a partially completed moccasin type shoe.

Referring to Fig. 1, the illustrated machine comprises a standard 20 upon which is mounted a head 22. Slidably mounted in bearings in the head are two parallel vertical shafts, one of which is shown at 24 in Fig. 1. A crosshead 26 is secured to the upper portions of the shafts 24 and yieldingly held against downward movement by springs 28 surrounding the shafts. A curved arm 30 extends forwardly and downwardly from the crosshead 26 and has secured to its lower end a plate 32. Two parallel plates 34 are secured to opposite sides of the plate 32 and extend downwardly beyond the lower end of the plate 32 and are provided at their lower extremities with a cross pin 36 which affords a mounting for any one of a plurality of movable dies for shaping moccasin toe pieces, one such die being shown at 38 in Fig. 1. For mounting the die 38 on the cross pin 36, a plate 40 is secured to a raised portion of the die and extends upwardly between the plates 34. The plate 40 is provided with a slot 42 which is open at the rear end of the plate and extends forwardly from its open end to the central portion of the plate then upwardly just far enough to provide a seat for the cross pin 36. The movable die 38 operates against a fixed die 44 removably mounted on the forward end of an arm 46 extending downwardly and forwardly from the head 22. Referring to Fig. 2, the movable die 38 is held against rocking movement by a screw 48 and a latch 56. The screw 48 is mounted in a lug 52 on the plate 32 and the latch 56 is pivotally mounted on a slide 57 which is adjustably secured to the plate 32 by a screw 59 extending through a longitudinal slot provided

in the slide. For taking the upward thrust against the latch 56 during the operation of the dies, a screw 50 is mounted in a lug 54 on the plate 32 and arranged to engage the upper end of the slide 57. By adjusting the screw 48 and the latch 56 vertically, the movable die 38 may be leveled or brought into parallelism to the fixed die 44. The fixed die 44 is removably mounted on the arm 46 in order to permit interchange of fixed dies of different sizes. To this end the arm 46 is provided at its forward end with a narrow extension or tongue 61 (Fig. 5) which fits into a groove 63 provided in the bottom of the fixed die 44. For locating the fixed die lengthwise of the tongue, a short stud 65 extends downwardly from the top of the groove 63 into a recess provided in the tongue 61. For yieldingly holding the fixed die 44 against upward movement away from the tongue 61, it is provided with a U-shaped flat spring 67 illustrated by dotted lines in Fig. 4. As shown in Fig. 5, this spring engages the bottom surface of the tongue 61 and holds the fixed die in position while permitting the die to be moved upwardly by the operator sufficiently to withdraw the stud 65 from the recess in the tongue to permit the die to be moved forwardly off the tongue.

For forming an elevation or convexity in the forward portion of a toe piece to give the toe piece a shape similar to the shape of the corresponding portion of the last on which the moccasin is to be shaped, the fixed die 44 has a raised portion 69 (Fig. 5) and the movable die 38 is provided with a concave recess 62 (Fig. 6) complementary to the raised portion of the fixed die. For forming an upstanding marginal flange in the toe piece, a thin curved plate 64 is secured to the fixed die 44 (Figs. 1 and 5) and arranged to extend upwardly beyond the upper surface of the die about one eighth of an inch, or slightly more than the thickness of the toe piece. Referring to Fig. 6, the plate 64 is spaced from the edge face of the movable die 38, when the die is in operating position as shown in Figs. 6 and 8, to the extent of the thickness of the toe piece and the downward movement of the die 38 causes the margin of the toe piece to be bent upwardly and brought into engagement with the edge face of the die thereby forming an upstanding flange thereon.

For operating the movable die 38 a treadle 39 is pivoted at its rear end between two brackets 76 and is connected by a link 41 to the horizontal arm of a bell crank lever 43 pivoted at its elbow to a lever 45 and pivoted at the upper end of its vertical arm to an L-shaped lever 47 which in turn is pivoted to the machine standard. The bell crank lever 43 and the L-shaped lever 47 act as a toggle to operate the lever 45 and a pin 49 at the end of the lever 47 limits the counter-clockwise movement of the bell crank lever 43 and determines the straightened position of the toggle as illustrated in Fig. 3. The rear end of the lever 45 is pivoted between the brackets 76 and its forward end is connected by an extensible link 51 to a cross head 151 connecting the lower ends of the shafts 24. For breaking the toggle upon release of the treadle 39 by the operator, the illustrated machine is provided with a spring 53, the upper end of which is connected to a lug extending forwardly from the lever 47 and the lower end of which is connected to the treadle. For holding the movable die 38 at the limit of its downward movement, as illustrated in Figs. 75

6 to 8, a treadle latch 55 (Fig. 1) is pivoted to the treadle 39 and arranged to engage a ratchet 69.

For working the margin at the toe end of a moccasin bottom into engagement with the flange formed in the toe piece, the illustrated machine is provided with a resilient presser member 66 (Figs. 1 and 4) which, as herein illustrated, is a piece of sheet rubber shaped to fit the top margin of the toe end of a vamp member and confined between two metal plates. This presser member moves lengthwise of the shoe toward its heel end to bring the top margin of the toe end of the vamp member into engagement with the marginal flange provided in the toe piece. Preferably, the end of the fixed die 44 has secured thereto a small piece of leather or similar substance 68 (Fig. 7) which has a form similar to the toe end of the last on which the shoe is to be shaped. The presser member 66, in working the margin of the vamp member into engagement with the flange of the toe piece, bends the toe end of the vamp member about the member 68 forming in it a bulge corresponding to the heightwise curvature of the toe end of a last, and contracting the side margins of the vamp member as it is brought into engagement with the flange of the toe piece (Fig. 8). The presser member 66 is provided with a stem 70 (Fig. 3) which is adjustably mounted in the forward end of a carrier 72. In its operation, the presser member moves upwardly from its rest position, illustrated in Fig. 1, to a position in which it is in alinement with the margin of the toe piece and then moves toward the toe piece in a downwardly inclined rectilinear path into its position illustrated in Fig. 3. For operating the presser member 66, the illustrated machine is provided with a treadle 74 (Fig. 1) which is pivoted at its rear end between the brackets 76. Also pivoted between the brackets 76 is an arm 78 the forward portion of which is connected to the treadle by a link 80. The arm 78 is connected by linkage 82 to the rear end of a lever 84 the forward portion of which is formed to provide a rectilinear guideway for the carrier 72 on which the presser member 66 is mounted. The lever 84 is pivoted between upward extensions of a pair of brackets 85 extending forwardly from the upper portion of the machine standard. The linkage 82 comprises a headed rod 86 slidably mounted in a sleeve 88 and surrounded by a spring 90 contained within the lower part of the sleeve and operating to hold the rod 86 yieldingly at the limit of its upward movement relatively to the sleeve. The treadle 74 operates through the connections above described to swing the lever 84 in a clockwise direction as seen in Fig. 1 until it is arrested by a roll 87 pivotally mounted between the forward ends of the brackets 85 and located within an arcuate slot 89 provided in a downward extension 98 of the lever 84. After the lever 84 comes to the limit of its clockwise movement, the presser member 66 is in longitudinal alinement with the toe piece held between the dies 38 and 44 and further depression of the treadle 74 operates through mechanism now to be described to slide the carrier 72 through the guideway provided in the lever 84 thereby to operate the presser member 66, the spring 90 in the linkage 82 permitting the linkage to extend to accommodate further downward movement of the treadle after the clockwise movement of the lever 84 is arrested. An upturned end portion 92 of the arm 78 is connected by a pair of chains 94 to the upper ends of a pair of levers 96 fixed to a cross shaft 97 in the down-

ward extension 98 of the lever 84. The lower ends of the levers 96 are connected by links 100 to a pair of levers 102 pivoted to the end of an arm 104 extending forwardly from the downward extension 98 of the lever 84. A spring 106 acts on the levers 102 to hold the carrier 72 yieldingly at the limit of its forward movement, said limit being determined by the engagement of the levers 102 with a stop member 108 (Fig. 1).

In accordance with the present invention, the illustrated machine is employed in practicing a method of making a novel type of moccasin shoe shown in Figs. 3 and 11, and illustrated and described in my co-pending application, Ser. No. 99,691, filed September 8, 1936. This shoe is provided with a vamp member which is secured to a sole before it is assembled with a toe piece. After being secured to the sole, the vamp member is normally in upstanding relation to the sole and its top margin is conveniently arranged for attachment to the toe piece. The toe end of a vamp member of this type is illustrated in Figs. 7 and 8 and identified by the numeral 110 and a toe piece 112 is illustrated in Figs. 5 to 8 at various stages in the operation of the machine. In accordance with the present method the toe piece is positioned on the fixed die 44 as illustrated in Fig. 5 with its margin extending beyond the plate 64. The operator positions the toe piece by eye, gaging the position of the periphery of the toe piece with relation to the edge face of the movable die 38 which he moves downwardly into adjacent relation to the toe piece for this purpose (Fig. 2). After the operator has positioned the toe piece on the fixed die 44 to his satisfaction, he operates the treadle 39 to force the movable die 38 downwardly into its position illustrated in Fig. 6 and the treadle latch 55 holds the treadle against return movement during the operation of the presser member 66. The operator then positions the vamp member 110 for attachment to the toe piece, locating its beveled edge face 118 opposite the beveled edge face 114 of the toe piece (Fig. 7). The operator then depresses the treadle 74 to cause the presser member 66 to move upwardly from its position illustrated in Fig. 1 into a position of alinement with the toe piece, then rearwardly in a rectilinear path toward the toe end of the vamp member. In the course of its rectilinear movement, the curved edge face of the presser member 66 engages the top margin of the vamp member, as shown in Figs. 4 and 8, and presses the beveled edge face of the vamp member against the beveled edge face of the toe piece with sufficient pressure to cause them to be bonded together by cement previously applied to said edge faces. While the toe end of the vamp member is held against the toe piece by the presser member 66, the operator manually presses the beveled margin at the sides of the vamp member against the beveled margin at opposite sides of the toe piece. The operator then releases the treadle 74 permitting the presser member 66 and its operating parts to return to their rest position by their own weight and unlatches the treadle 39 whereupon the springs 28 lift the movable die 38 away from the toe piece and return the treadle 39 and its connections to their rest positions.

The movable die 38, in the course of its operation on the toe piece 112, bends the margin of the toe piece downwardly about the raised portion 60 of the fixed die 44 causing a substantial contraction of the margin of the toe end of the toe piece. The contracted condition of the marginal 75

portion of the toe piece thus produced is secured and maintained by the cement attachment of the beveled edge face 118 of the vamp member to the beveled edge face of the toe piece. In bending 5 the toe end of the vamp member about the member 68 on the fixed die 44, the presser member 66 moves in a rectilinear path pressing the margin at the toe end of the vamp member against the toe piece without any gathering action or contraction of the toe portion of said margin. It 10 will be understood, however, that this operation substantially reduces the length of the beveled top margin of the vamp member and contracts the side portions of said margin. The side margins of the toe piece, since they are not themselves contracted in the course of the assembling operation, are capable of maintaining the contracted condition of the side portions of the top margin of the vamp member after cement 15 attachment of said margins, thus promoting the continuance of the rounded or bulged condition created at the toe end of the vamp member by the operation of the presser member 66. Similarly the top margin at the toe end of the vamp 20 member, since it is not contracted by the operation of the presser member 66, is capable of maintaining the contracted condition created in the toe end of the toe piece by the operation of the movable die 38, thus maintaining the convexity 25 formed in the toe piece.

After the assembled shoe is removed from the illustrated machine, the toe piece is permanently secured to the vamp member by a seam extending through their beveled margins. This seam 30 may be sewn by hand or by a machine such as that illustrated and described in United States Letters Patent No. 1,950,386, granted March 13, 1934, on an application filed in the name of Fred Ashworth. This seam not only permanently 35 secures the toe piece to the vamp member, but affords further means for maintaining the contracted condition created at opposite sides of the top margin of the vamp member and the contracted condition produced at the toe end of the toe piece. The bulge in the toe end of the vamp 40 member and the convexity in the toe piece give the forepart of the shoe the general shape of the forepart of the last on which the shoe is mounted after the stitching operation, and consequently 45 there is little if any stretching of the stock of the forepart of the shoe in mounting it on its last and for this reason the forepart of the shoe is likely to retain the shape of the forepart of the last permanently.

50 Certain styles of shoes of the type above described are not bulged at the toe end as is the shoe, the toe end of which is illustrated in Fig. 8. In assembling shoes of this type in accordance with the method of the present invention, the member 68 at the toe end of the fixed die 44 is omitted in order that the upstanding portion of the toe end of the vamp member will remain substantially straight, as illustrated in Fig. 7, after the assembling operation has been performed. 55 In assembling such shoes the presser member 66 may be dispensed with, if desired, and the toe end of the vamp member manually attached to the toe piece.

Having thus described my invention, what I 60 claim as new and desire to secure by Letters Patent of the United States is:

1. In a machine for use in the manufacture of shoes having moccasin toe pieces, a toe piece supporting means including means projecting 65 from the supporting means and constructed and

arranged to engage the margin of a toe piece supported thereon, and means co-acting with said supporting means to form a marginal flange in the toe piece, the height of said projecting means being substantially less than the width of 5 said marginal flange.

2. In a machine for use in the manufacture of shoes having moccasin toe pieces, a toe piece supporting member having a projection constructed and arranged to engage the margin of 10 a toe piece supported thereon, said projection providing one wall of a recess in the work supporting member, and means for forcing the main portion of the toe piece into said recess and thereby forming a flange in its margin, the 15 height of said wall being substantially less than the width of said flange.

3. In a machine for use in the manufacture of shoes having moccasin toe pieces, a pair of toe piece engaging members constructed and arranged to hold the toe piece between them, and means for pressing the top margin of a shoe part 20 against the margin of the toe piece.

4. In a machine for use in the manufacture of shoes having moccasin toe pieces, a pair of toe piece engaging members constructed and arranged to hold the toe piece between them, and a member for pressing the toe portion of the top margin of a shoe part against the margin of the toe 25 end of the toe piece.

5. In a machine for use in the manufacture of shoes having moccasin toe pieces, a presser for pressing the top margin of a shoe part against a supported toe piece, a carrier for the presser, and means operable to move the carrier in one direction to a predetermined limit to position the presser in longitudinal alinement with the supported toe piece and in another direction to cause the presser to press the top margin of said shoe part against the margin of the toe piece. 30

6. In a machine for use in the manufacture of shoes having moccasin toe pieces, a presser for pressing the top margin of a shoe part against the margin of a supported toe piece, a carrier for the presser, a member on which the carrier is mounted, and an actuator which first moves said member to transfer the presser from a remote position into longitudinal alinement with the supported toe piece and which thereafter moves the carrier in a rectilinear path relatively 45 to said member to advance the presser longitudinally of the toe piece and cause it to press the top margin of said shoe part against the margin of the toe piece. 50

7. In a machine for use in the manufacture of shoes having moccasin toe pieces, a presser for pressing the top margin of a shoe part against a supported toe piece, a carrier for the presser, a lever in which the carrier is slidably mounted for rectilinear movement, and an actuator which first operates on the lever to transfer the presser from a remote position into longitudinal alinement with the supported toe piece and then operates on the carrier to advance the presser longitudinally of the toe piece thereby to press the top margin of said shoe part against the margin of the toe piece. 55

8. In a machine for use in the manufacture of shoes having moccasin toe pieces, a presser for pressing the top margin of a shoe part against the margin of the toe piece, a carrier for the presser, a lever in which the carrier is mounted for longitudinal movement relatively to the lever, said lever being movable to transfer the presser from a remote position into longitudinal alinement. 7

ment with the supported toe piece, a stop for arresting the lever after it has so transferred the presser, and means for advancing the presser longitudinally of the supported toe piece to press the top margin of said shoe part against the margin of the supported toe piece.

9. In a machine for use in the manufacture of shoes having moccasin toe pieces, a pair of dies having the general shape of a moccasin toe piece and provided respectively with convex and concave surfaces constructed and arranged to co-act on a toe piece positioned between them to form a convexity therein, and a member on one of said dies for forming a marginal flange in the toe piece.

10. In a machine for use in the manufacture of shoes having moccasin toe pieces, a die provided with a convex surface which acts on a toe piece to form a convexity therein, and means for forming a marginal flange in the toe piece including a flange former projecting from said die.

11. In a machine for use in the manufacture of shoes having moccasin toe pieces, a die provided with a convex surface which acts on the toe piece to form a convexity therein, a flange former projecting from said die, and another die constructed and arranged to co-act with the first-mentioned die in convexing and flanging the toe piece.

12. In a machine for use in the manufacture of shoes having moccasin toe pieces, a die having the general shape of a moccasin toe piece and provided with a convexity for shaping the toe piece, a flange former projecting from the periphery of said die, and another die provided with an edge face constructed and arranged to co-act with the flange former to form a marginal flange in the toe piece.

13. In a machine for shaping moccasin toe pieces, a support for any one of a plurality of interchangeable toe piece shaping dies, a carrier constructed and arranged to receive any one of a plurality of interchangeable toe piece shaping dies, means for actuating the carrier to cause a die mounted thereon to co-act with a die on the support to shape a toe piece positioned between them, and means on the carrier for positioning a die mounted thereon in parallelism to a die on said support.

14. In a machine for shaping moccasin toe pieces, a support for any one of a plurality of interchangeable toe piece shaping dies, a carrier constructed and arranged to receive any one of a plurality of interchangeable toe piece shaping dies, means for actuating the carrier to cause a die mounted thereon to co-act with a die on the support to shape a toe piece positioned between them, means on the carrier for positioning a die mounted thereon in parallelism to a die on said support, and a latch for holding a die in determinate position on the carrier.

15. In a machine for shaping moccasin toe pieces, a support for any one of a plurality of interchangeable toe piece shaping dies, a carrier constructed and arranged to receive any one of a plurality of interchangeable toe piece shaping dies, means for actuating the carrier to cause a die mounted thereon to co-act with a die on the support to shape a toe piece positioned between them, and a carrier constructed and arranged to receive any one of a plurality of presser members for pressing the top margin of a shoe part against the margin of a toe piece held between said dies.

16. That method of making shoes having moccasin toe pieces which comprises forming a mar-

ginal flange in a moccasin toe piece between dies, and while the toe piece is held between the dies securing the top margin of a shoe part to the marginal flange of the toe piece.

17. That method of making shoes having moccasin toe pieces which comprises forming a marginal flange in a moccasin toe piece between dies one of which affords an abutment for the flange thus formed, and while the toe piece is held between the dies with its marginal flange against said abutment securing the top margin of a shoe part to the marginal flange of the toe piece.

18. That method of making shoes having moccasin toe pieces which comprises forming a convexity in the interior of a loose toe piece, and thereafter attaching the toe piece to another shoe part.

19. That method of making shoes having moccasin toe pieces which comprises contracting the forward margin of a toe piece thereby to form a convexity in the interior of the toe piece, and attaching the toe piece thus formed to another shoe part.

20. That method of making shoes having moccasin toe pieces which comprises providing a toe piece and a vamp member, bending the margin at the toe end of the vamp member inwardly over a form to produce a bulge therein, simultaneously contracting the top margin at the sides of the vamp member, and thereafter attaching the toe piece to the vamp member.

21. That method of making shoes having moccasin toe pieces which comprises providing a toe piece and a vamp member, bending the margin at the toe end of the vamp member inwardly over a form to produce a bulge therein, simultaneously contracting the top margin at the sides of the vamp member, forming a convexity in the interior of the toe piece, and thereafter attaching the toe piece to the vamp member.

22. That method of making shoes having moccasin toe pieces which comprises contracting the margin at the toe end of a toe piece, bending the toe end of a vamp member over a form to produce a bulge therein, simultaneously contracting the top margin at opposite sides of the vamp member, and thereafter attaching the toe piece to the vamp member edge to edge.

23. That method of making shoes having moccasin toe pieces which comprises contracting the margin at the forward end of a toe piece, forming a peripheral flange in the toe piece, and thereafter attaching a vamp member to the toe piece edge to edge.

24. That method of making shoes having moccasin toe pieces which comprises contracting the forward margin of a toe piece thereby to form a convexity in the interior of the toe piece, positioning a vamp member relatively to the toe piece with their top edges in alinement, forming a bulge in the toe end of the vamp member, in the formation of said bulge contracting the top margin at opposite sides of the vamp member while leaving said top margin substantially non-contracted at the toe end of the vamp member, and securing the contracted condition of said shoe parts by uniting the contracted forward margin of the toe piece to the non-contracted margin at the toe end of the vamp member and uniting the contracted margins at opposite sides of the vamp member to the non-contracted side margins of the toe piece.

25. That method of making shoes having moccasin pieces which comprises forming a convexity in the interior of a toe piece, in the forma-

tion of said convexity contracting the forward margin of the toe piece, and securing the contracted condition of the margin of the toe piece by means of a sewn seam.

- 5 26. That method of making shoes having moc-
casin toe pieces which comprises forming an ele-
vation in the interior of a toe piece, in the forma-
tion of said elevation contracting the forward
margin of the toe piece, and securing the con-
tracted condition of the toe piece by means of a
10 sewn seam uniting the toe piece to another shoe
part.

27. That method of making shoes having moc-

casin pieces which comprises forming a convex-
ity in the interior of a toe piece, in the formation
of said convexity contracting the forward margin
of the toe piece, forming a bulge in the toe end
of a vamp member, in the formation of said
bulge contracting the top margin at opposite
sides of the vamp member, and securing the con-
tracted condition of the forward margin of the
toe piece and opposite sides of the vamp member
by means of a sewn seam uniting the toe piece to
the vamp member, edge to edge.

KARL ENGEL.
